CAKE PLATE

Marvin G. Yutzey, Moundsville, W. Va., assignor
to Fostoria Glass Company, Moundsville,
W. Va., a corporation of West Virginia

Application April 29, 1948, Serial No. 146,032

Term of patent 14 years

(Cl. D36—2)

To all whom it may concern:

Be it known that I, Marvin G. Yutzey, a citizen of the United States of America, residing at Moundsville, in the county of Marshall and State of West Virginia, have invented a new, original, and ornamental Design for a Cake Plate, of which the following is a specification, reference being had to the accompanying drawings, forming a part thereof, wherein:

Fig. 1 is a top plan view of a cake plate showing my new design;

Fig. 2, a side elevational view illustrating the handled side;

Fig. 3, a side elevational view showing the opposite side;

Fig. 4, a horizontal sectional view on the line 4—4 of Fig. 3; and,

Fig. 5, a horizontal sectional view on the line 5—5 of Fig. 4.

I claim:

The ornamental design for a cake plate, as shown.

MARVIN G. YUTZEY.
